JOHANN ADAM WILHELM FICKENSCHER, OF DRESDEN-BLASEWITZ, GERMANY.

GRINDING ROLL CHAIR.

Application filed April 27, 1926, Serial No. 105,009, and in Germany December 27, 1924.

- This invention relates to grinding mills and has for its object to produce a grinding mill having a number of passes or grinding gaps equal to the number of grinding rolls.
- 5 According to the present invention a number of grinding rolls, not less than four, are arranged in series with each roll of the series in a position which enables it to coact with two other rolls of the series, so as to form 10 a number of grinding gaps equal to the number of rolls, means being provided for positively rotating the rolls, each roll in the opposite direction to that of the rolls with which it coacts and with the peripheral speed 15 of the second and each subsequent roll which precedes it.
- The object of the invention is to provide 20 a grinding roll chair of this type wherein the rolls cooperate, with successively increasing velocity, to form a number of grinding gaps equal to the number of rolls, and in which the material, is carried along by the more rapidly rotating roll, passes alternately to the interior and exterior of the annular 25 series of rolls and is finally scraped off the last roll after being ground between it and the first roll.
- Owing to the rolls of the rolling mechanism being arranged in such a way that 30 their peripheries circumscribe a closed figure, and to the number of rolls being an even number not less than four, the material to be ground is guided in a sinuous line from one rolling gap to another all round the said 35 closed figure. After it has been worked for the last time between the last roller and the first it is scraped off from the last roll. In a manner which is known in connection 40 with roll chairs of other kinds the relative speeds increase between each co-operating pair of rolls from the inlet gap to the last grinding gap, as a result of which the feeding forward of the material in the desired manner is ensured.
- 45 The arrangement according to the invention has the advantage that there are just as many roll gaps working as there are rolls, since the last roll in its turn co-operates with the first. Hence, as compared with the 50 usual series arrangement, one roll is saved. Furthermore, however, there is also a substantial saving in sliding bearings and in adjusting devices, because in the case of four rolls two can be journalled in stationary bearings, and more than two in the case of a larger number of rolls, thereby cheapen-
- ing the manufacture of the machine. Furthermore as compared with a roll chair having rolls arranged in series horizontally, the floor area required by the machine is diminished without thereby rendering the feeding of the material to be ground more difficult by having to supply it at a greater height, as would be necessary in the event of the rolls being superposed in a vertical or inclined row.
- 55 Figures 1 and 2 of the accompanying drawings show a grinding roll chair with four rolls, *a*, *b*, *c*, and *d*, arranged in accordance with the present invention, to form 70 four grinding gaps, I, II, III, IV, through which the material being ground passes in succession. The driving of the rolls is effected by means of spur wheel gearing provided at the ends of the rolls on both sides 75 of the machine, the gearing being so designed that the speed of revolution of the rolls increases from *a* through *b* and *c* to *d*. For example, *a* may make 20 revolutions per minute, *b* 40, *c* 80 and *d* 130, or other 80 speeds of revolution may be selected in the same proportion. The directions of rotation correspond to the directions shown in the drawing by arrows. In the space located above the rolls *a* and *b* and therefore 85 outside the closed figure I, II, III, IV a filling trough *e* is fitted. Against the periphery of the roll *d*, at a point within the closed figure I, II, III, IV, there bears a scraper 90 *f*. Two of the rolls, *a* and *c* for example, 95 are journalled in stationary bearings, while the other two, *b* and *d*, are adjustable in a known manner by means of screw spindles *h* and *i* for the purpose of enabling the contact gaps to be narrowed or widened.
- 95 The material to be ground comes, in the filling trough *e*, into contact with the two rolls *a* and *b*, which draw it through the gap I. The difference between the peripheral velocities of the rollers *a* and 100 *b* gives rise to a relative slipping of the surfaces of these rolls at I, thereby imparting to the material its first grinding treatment. Since the angular velocity of the roll *b* is greater than that of the roll *a*, and since 105 it is found by practical experience that the material being ground always remains adhering to the more rapidly rotating roll, the material is carried forward along the inner side of the roll *b*, that is to say, the side facing the interior of the closed figures I, II, 110 III, IV, to the gap II, where the same grind-

ing takes place as at the gap I. In a similar manner the material is carried away upon the faster roll *c*, but upon the outer side thereof, that is to say, the side remote from the 5 other rolls. On the roll *c* the material reaches the gap III, and is there treated again, after which it passes round the inner side of the roll *d*, and is finally carried to the gap IV between the rolls *d* and *a*, where 10 the fourth treatment takes place. In consequence of the great difference between the peripheral velocities of the rolls *a* and *d* this stage of the treatment is the most intensive. The scraping knife *f* finally scrapes 15 off the ultimate product from the outer side of the roller *d*, and it collects in the receiver *g*. Hence, according to the invention, there are formed as many successive grinding gaps acting upon the material as there 20 are rolls, so there is a saving of one roll as compared with the usual series arrangement of rolls in the case of roll chairs with progressive grinding of the material in a plurality of successive roll gaps.

25 It may happen under some circumstances that the material passing between the rolls *a* and *b* is not completely removed by the roll *b* from the roll *a*. The material which remains adhering to the roll *a* would then 30 pass directly to the last grinding gap, between the rolls *a* and *d*, and would thus only be ground twice instead of four times. This is obviated by a scraper arranged at *x* 35 between the rolls and acting upon the roll *a*. What it scrapes off falls on to the roll *c* and thus passes through the grinding gap II between *b* and *c* and then through the two other grinding gaps, so that it also is ground four times.

40 What I claim is:—

1. In a grinding mill in combination, an even number of grinding rolls not less than four arranged in series with each roll of the series in a position for enabling it to coact with two other rolls of the series so as to form a number of grinding gaps equal to the number of rolls, means for positively rotating said rolls, each roll in the opposite direction to that of the rolls with which it coacts and with the peripheral speed of the second and each subsequent roll greater than that of the roll that precedes it, means for supplying material to be ground to the grinding gap between the first and second rolls of the series, and means for removing ground material from the last roll.

2. In a grinding mill in combination, an even number of rolls not less than four arranged in series with each roll of the series in a position for enabling it to coact with two other rolls of the series so as to form a number of grinding gaps equal to the number of rolls, means for displacing alternate rolls of the series for varying the widths of said gaps two at a time, means

for positively rotating said rolls, each roll in the opposite direction to that of the rolls with which it coacts and with the peripheral speed of the second and each subsequent roll greater than that of the roll that precedes it, 70 means for supplying material to be ground to the grinding gap between the first and second rolls of the series, and means for removing material from the last roll.

3. In a grinding mill in combination, an even number of rolls not less than four arranged in series with each roll of the series in a position for enabling it to coact with two other rolls of the series so as to form a 75 number of grinding gaps equal to the number of rolls, means for displacing alternate rolls of the series for varying the widths of said gaps two at a time, said means comprising slidable bearings for the said alternate rolls, and means for adjusting the 80 positions of said slidable bearings, means for positively rotating the rolls, each roll in the opposite direction to that of the rolls with which it co-operates and with the peripheral speed of the second and each subsequent roll greater than that of the roll 85 that precedes it, means for supplying material to be ground to the grinding gap between the first and second rolls of the series, and means for removing ground material from the last roll.

4. In a grinding mill in combination, an even number of rolls not less than four arranged in series with each roll of the series in a position for enabling it to coact with two other rolls of the series so as to form a 100 number of grinding gaps equal to the number of rolls, means for positively rotating said rolls, each roll in the opposite direction to that of the rolls with which it co-operates and with the peripheral speed of the second and each subsequent roll greater than that of the roll that precedes it, means for supplying material to be ground to the grinding gap between the first and second rolls of the series, and means for removing ground material from the last roll.

5. In a grinding mill in combination, an even number of rolls not less than four arranged in series with each roll of the series in a position for enabling it to coact with two other rolls of the series so as to form a 110 number of grinding gaps equal to the number of rolls, slidable bearings for alternate rolls of the series, screw spindles for adjusting the positions of said slidable bearings to vary the widths of the grinding gaps, spur gears for positively rotating said rolls, each roll in the opposite direction to that of the rolls with which it coacts and with the 115 peripheral speed of the second and each sub- 120

125

130

sequent roll greater than that of the roll the last grinding gap after passing through that precedes it, means for supplying material to be ground to the grinding gap between the first and second rolls of the series, a scraper for removing any material that may adhere to the periphery of the first roll and preventing it from passing to the last grinding gap after passing through the first grinding gap, and a scraper for removing ground material from the last roll. In testimony whereof I have signed my name to the specification.

JOHANN ADAM WILHELM FICKENSCHER.
